SHOE FITTING DEVICE

Elmer J. Bliss, Boston, Mass., assignor to Regal Shoe Company, Whitman, Mass., a corporation of Massachusetts

Application December 26, 1933, Serial No. 703,876

5 Claims. (Cl. 33—3)

This invention relates to the measurement of feet for the purpose of fitting shoes and is intended to provide a simple, compact and convenient device of inexpensive construction which is capable of use for quickly and accurately ascertaining both the length and the width size measurements of feet when in the expanded or extended position such as the feet assume when carrying the weight of the person in walking.

Generally speaking, the present improvement embraces an approximately sector-shaped length gauging plate or member provided at its arcuate edge with a series of upturned toe gauging members arranged at different distances from a common center in correspondence with a progressive series of length size measurements, according to a basic or standard scale, combined with a foot supporting plate or member pivotally mounted to swing about said center and having oppositely flared width size gauging members so correlated with the length of the foot that an accurate indication of both length and width measurements is obtained by direct reading of the size indicating symbols.

In the accompanying drawing is illustrated a simple and effective embodiment of the principles of this invention, in which

Fig. 1 is a plan view showing the foot supporting width gauging element cooperatively assembled with the length measuring member or pan by which a direct reading, indicative of the width and length size measurements, is given for an interposed foot.

Fig. 2 is a vertical section on the plane indicated by sectional line 2—2 of Fig. 1.

In an earlier filed application, Serial No. 616,460, which matured into Patent No. 1,951,322 issued March 13, 1934, I have described a type of construction for a foot size measuring device in which the foot-receiving and width-gauging member was slideable along an elongated pan provided with upturned toe gauging members intended to secure the same results that are effected by the present device, but that particular form of construction disclosed in my said earlier application involved the use of a considerably greater amount of metal and was very much less compact than is the present form which embodies a similar principle.

In the practice of the invention according to the form herein illustrated, I provide an approximately sector-shaped pan 1 which is provided near its apex with a fulcral guiding member 2, in this case, comprising a cylindrical cup-like member suitably secured, as by rivets, to the apical portion of the pan. At intervals along the arcuate or peripheral edge opposite the centralizing guide 2 a series of radially offset toe gauging lips 3 is formed by upturning relatively narrow portions of the metallic pan. These upturned lips

or gauge members may of course be formed in any appropriate manner so long as they form an upward projection adapted to abut against the toe of a foot being measured. A full size device will have these toe gauging members arranged in a progressively offset series, each one being $\frac{1}{6}$ inch farther from the radial center than the one to the left of it, since in foot measuring the difference between one length size and the next full length size amounts to $\frac{1}{3}$ inch. The number of toe gauging lips 3 that will be provided on any plate or pan depends upon the range of foot measurements for which the pan is intended.

Coordinated with this length gauging pan is a foot-receiving or foot-supporting plate or member 4 preferably having an elevated or raised heel portion 4^a, so that the raising of the heel tends to throw the weight of the person standing on the measuring device slightly forward for the purpose of causing expansion or extension of the foot similar to the extension produced while the foot is supporting the weight in the act of walking.

The rear end edge of the heel portion 4^a is provided with an upstanding heel gauge 5 against which the heel of the foot should always contact when the foot is being measured.

The forepart of the foot-receiving and width-gauging member is provided with upstanding, forwardly flared flanges 6 constituting width-gauging members which diverge according to a definite ratio. As is well known to those skilled in the art, while length sizes in foot measuring step up by increments of $\frac{1}{3}$ inch for the over-all length measurement, the ball length, that is, the length from the heel to the ball joint, is generally assumed to be equal to $\frac{2}{9}$ of the over-all length, hence the length increments of ball length measurement of a No. 8 foot is $2/9$ inch, instead of $\frac{1}{3}$ inch. As is also well known, width size measurements increase by successive stages or increments equal to $\frac{1}{12}$ inch. Width size increments are designated either by letters A, B, C etc. or by numerals, 1, 2, 3, 4, etc., but these width size symbols, unlike the length size symbols, are variable since a No. 8—C foot has a width measurement $\frac{1}{12}$ inch greater than a foot designated as No. 7—C and $\frac{1}{12}$ inch less width measurement than a foot designated as No. 9—C. Consequently, in laying out the divergent side gauges 6, the divergence for each $2/9$ inch from the heel gauge would increase $\frac{1}{12}$ inch, so that a No. 8 foot, let us say, of E width would form gauging contact across the ball thereof with the flanges 6, while a No. 7—E foot would likewise form gauging contact with the side gauges 6 but $2/9$ inch nearer the heel gauge than would the ball of the No. 8—E foot.

To correctly gauge narrower widths of foot according to the same principle, there is provided

a series of gauging strips 7 pivotally connected at their forward ends to the side gauges or flanges 6 by means of transverse rivets 6a. There are four such width-gauging members shown in Fig. 1 of the drawing. When they are all raised or thrown forward, so that there is gauging contact between the flanges 6 and the opposite sides of the ball portion of the foot, they will signify, in this case, that the interposed foot gauging 10 against the heel gauge 5 has an E width, while its length is determined by the engagement of the tip of the toe with the appropriate length size gauging lip.

If the foot does not form gauging contact with the flanges 6, then one or more of the width-gauging members 7 can be shifted into gauging position until gauging contact is established against opposite sides of the foot. As these gauging strips or members are made $\frac{1}{2}$ inch in thickness, it will be seen that when all four of them are in gauging position, as shown in Fig. 1, the width gauge indication then will signify an A width; with three of them in gauging position the indication or reading will indicate a B width, 25 and so on.

To facilitate the sliding of the width-gauging and foot-receiving member 4, I prefer to provide ball domes 8 riveted to the underside of the fore-part of the width-gauging member 4.

30 In practice, the foot to be measured is placed upon the width-gauging member 4 with the heel resting in contact with the heel gauge 5 and the foot is turned until the forwardly projecting tip of the great toe grazes the appropriate length-gauging lip 3. The width-gauging strips are then manipulated to give a proper gauging contact with the opposite sides of the ball portion of the foot and the reading is then taken from the toe gauge scale and according to the number of 35 width-gauging strips in gauging position. Numerals are frequently used now as width indicating symbols and in that case when all the width gauges are in gauging or active position according to the present illustration that would indicate a No. 1 width and the inside width gauge on the left side is provided with a single mark. If, in order to properly gauge the width, this 40 No. 1 gauge is moved to inactive position, the size then indicated would be No. 2 marked on the inside gauge at the right. If it be required to move this gauge to inactive position to secure correct width-gauging, then the lowest number of the remaining gauges is 3, equivalent to a C width.

45 Of course it is important that the two co-acting members be accurately positioned with reference to each other so that they will always have a common pivotal center. This fulcral joint may be constructed in any desired manner, but in the 50 present case I have shown a cup 9 with a cylindrical flange snugly fitting around the cylindrical flange of the pivot member 2 and riveted to the bottom of the heel portion of the width-gauging member, so as to have a telescopic engagement with the fulcral member 2. This permits quick detachment of the two members and equally quick assemblage. The device is compact and requires considerably less material in its construction than does the earlier form of the 55 invention disclosed in my aforesaid pending application.

70 What I claim is:

1. A foot measuring device embracing in its construction an approximately sector-shaped length-gauging member having arranged along

its peripheral edge an arcuate series of radially offset toe-gauging members and a foot-receiving and positioning plate pivotally connected at its heel supporting portion with the apical portion of said sector, and being provided with divergent width-gauging members arranged to form gauging contact with opposite sides of the ball portion of an inserted foot to indicate in conjunction with a toe-gauging member the length and width size measurements of an inserted foot.

2. A foot measuring device embracing in combination a sheet metal length-gauging element of approximately sector-shape provided along its arcuate edge with a series of upturned toe-gauging lips arranged, respectively, at progressively greater radial distances from a common center, and a foot-receiving, width-gauging element whose rear portion is provided with a heel stop and is pivotally connected with said sector element at the heel portion, said foot-receiving element being provided at its opposite sides with upstanding width gauges for ascertaining in conjunction with the appropriate toe-gauging lip the width size measurement of an inserted foot.

3. A foot measuring device embracing in combination a sector-shaped plate having an arcuate series of upwardly projecting fixed toe-gauging members arranged at progressively increased radial distances from a common center located in the apical portion of the plate and a foot-receiving element having pivotal connection with said plate to permit its pivotal movement about the heel portion of said plate, said foot-receiving element being provided at its opposite sides with adjustable width-gauging members for indicating in conjunction with the appropriate toe-gauging lip the length and width measurements of an inserted foot.

4. A foot measuring device embracing in combination an approximately sector-shaped sheet metal plate provided with an arcuate series of upwardly turned integral toe-gauging lips at different distances from a common center and having at its apical portion a fulcral guide, and a foot-positioning and receiving element comprising a raised heel portion having pivotal connection with said guide member and having at its rear edge an upturned heel stop, the forward portion of said foot-positioning member being provided with divergent upturned width caliper flanges and a series of cooperating gauges pivotally connected with said flanges to be folded inside the flanges and removed away from said flanges, thereby providing means for accurately gauging the ball width of an inserted foot in conjunction with the appropriate toe-gauging lip and thus indicate the length and width size measurements of the foot.

5. A foot measuring device embracing a plate provided with an arcuate series of upstanding toe gauges arranged at progressively increased distances from a common center, and a foot-positioning width measuring element having swivelled connection with said plate and having at its rear end a heel gauging stop forming in conjunction with the appropriate toe-gauging lip a size length caliper and adjustable width-gauging members arranged on opposite sides of the forepart of said foot-positioning member to indicate the width size measurement of an inserted foot, said forepart being provided with underneath castor domes for slidingly supporting the forepart upon said plate.
